[57] CLAIM

The ornamental design for device for enclosing trash
container and displaying information, as shown and
described.

DESCRIPTION

FIG. 1 is a top perspective view of a device for enclosing
trash container and displaying information showing
our new design;

FIG. 2 is a side elevational view thereof, the view from
all sides being identical thereto;

FIG. 3 is a top view of the device shown in FIG. 1; and,
FIG. 4 is a bottom view of the device shown in FIG. 1.

FIG. 1

FIG. 2

FIG. 3

FIG. 4
